MOVABLE SUPPORT

Butler Ames, Boston, Mass.

Application May 1, 1940, Serial No. 332,655

8 Claims. (Cl. 155—22)

This invention relates to an improvement in a movable support of the type which can be pushed along and will serve as a support for the user when in motion or at rest. Such a support is of value not only for those people who are infirm and have difficulty in walking or standing but also for anyone desiring to rest from time to time as, for example, an attendant at a football or baseball game or at any spectacle where seats are not provided or are not available.

The present invention is a further development of that shown in my copending application Serial No. 287,730, filed August 1, 1939, which matured into Patent No. 2,224,246 on December 10, 1940 and has as its primary object the provision of a movable support so constructed that, when not in use, it can be collapsed to facilitate storage or transportation; and that it includes means by which it is rigidly secured in both operative and collapsed positions, all as will be hereinafter described and claimed.

As illustrating this invention one embodiment is shown in the accompanying drawings wherein

Fig. 1 is a view in side elevation of a movable support embodying this invention;

Fig. 2 is an end elevation of such support;

Fig. 3 is a top plan view of such support when collapsed;

Fig. 4 is a side elevation of the collapsed support;

Fig. 5 is an enlarged view with parts broken away of a detail of such support; and

Figs. 6 and 7 are plan views of the coacting faces of a sleeve and collar which when engaged act to hold the support in the desired operative or collapsed positions.

The support 10 comprises a pair of side frames 15 connected at one end by means which rigidly hold the frames in the desired position. Each side frame comprises a front leg 16, a back leg 17 and a bar 18 by which the tops of the legs are connected. Preferably, as shown in the drawings, the legs 16 and 17 and the bar 18 are formed from a suitably bent tube. The legs 16 and 17 are connected intermediate their ends by a brace bar 19 parallel to the bar 18 and welded, soldered or otherwise secured at its ends to the legs. The front leg 16 terminates in a fork 20 between the legs of which a wheel 21 is rotatably mounted upon a shaft 22 while the lower end of the back leg 17 is bent outwardly and upwardly and carries a rod 23 which acts as a skid or shoe.

The unit 25 by which the side frames 15 are connected comprises a pair of crossbars 26 and a pair of sleeves 27 to which the ends of the bars are secured. Each sleeve 27 surrounds and is movable relative to a leg 17 and rests upon a collar 28 fixed to the leg. The lower face of the sleeve is provided with pairs of diametrically op-

posite notches 29 and 30 and the upper face of the collar 28 has diametrically opposite posts 31. The interengagement of the notches and posts hold the sleeve 27 against rotation and the sleeve is clamped in such position by a nut 32 meshing with a threaded nipple 33 fixed onto the leg 17 above the sleeve. The nipples 33, as shown in Fig. 5, limit the upper movement of the sleeves 27.

10 The legs 17 are rearwardly inclined and the crossbars 26 are parallel, the upper bar being shorter than the lower bar so that the side frames are inclined outwardly. Thus the support stands firmly and resists any tendency to tip either rearwardly or laterally when set up as shown in Figs. 1 and 2, with the posts 31 seated in the notches 29.

When the support is to be collapsed the nuts 32 are backed away from the sleeves 27 and the 20 latter raised out of contact with the collars 28. The connecting unit 25 is then swung about the leg 17 of one side frame 15 in either direction into contact therewith, while the other side frame is swung through 180° about that unit so that the parts of the support take the position shown in Figs. 3 and 4 with the leg 16 of each side frame near and in advance of the leg 17 of the other side frame. The sleeves 27 are then clamped in contact with the collars 28 by tightening the nuts 32, with the posts 31 seated in the notches 30 so that the support will remain in the collapsed position.

It will be noted (see Figs. 6 and 7) that the notches 29 are of substantially the same length 35 as the posts 31 so that when the support is set up the side frames 15 are firmly held in position against undue movement relative to the connecting unit 25. The notches 30, however, are longer than the posts 31. This is due to the fact that 40 when the support is collapsed the side frames are at a slight angle to the cross bars since obviously it is impossible for them to be in the same plane. The length of the notches 30 is such that when the support is collapsed the ends of the posts 31 will bear against those ends of the notches 30 which prevent any movement of the side frames away from the unit 25. The contact of the legs 17 with the brace bars 19 prevents any further movement of the side frames toward the unit. Consequently the spacing of the other ends of the posts from the other ends of the notches (see Fig. 4) due to the difference in length of the posts 31 and notches 30, does not result in any relative movement of side frames and crossbars. 45

50 The difference in length, however, is important because it permits the support to be collapsed with either face of the side frames exposed.

In order that the support be easily moved when collapsed it is so constructed that it rests solely upon the wheels 21, the skids 23 being raised as shown in Fig. 4. The condition is attained in the

following manner. The angle 35 made by the back leg 17 and the bar 18 is slightly less than the angle 36 made by the front leg 16 and that bar and the angle 37 made by the brace bar 19 with the back leg 17 is approximately equal to the angle 38 made by either crossbar 26 with the sleeve 27 of the connecting unit 25. Hence when the parts are collapsed the legs 17 are raised by the action of the connecting unit so that they take the positions shown in Fig. 4.

The support may also be provided with a seat which is preferably of the type that may be kept out of the way when the support is being moved. The seat with which the support 10 is shown provided comprises a strip 40 of canvas, carpeting or the like, one end of which is looped around the upper crossbar 25, and the other end is secured to a roll or rod 41. Mounted upon the brace bars 19 are brackets 42 which may be of any suitable type to engage the ends of the roll 41 and prevent it from moving toward the legs 17.

While one embodiment of the invention has been shown and described it will be understood that the invention is not limited thereto and that other embodiments of the invention may be made without departing from the spirit and scope thereof, as set forth in the following claims.

I claim:

1. A movable support comprising side frames, each frame including front and back legs, a unit connecting such frames, said unit including at each end a sleeve which is mounted upon one leg of the side frame, and means for locking said unit in position upon the side frames, said locking means at each side frame including a collar carried by a leg on which a sleeve rests and means for clamping said sleeve against said collar.

2. A movable support comprising side frames, each frame including front and back legs, a unit connecting such frames, said unit including at each end a sleeve which is mounted upon one leg of the side frame, and means for locking said unit in position upon the side frame, said locking means at each side frame including a collar on which the sleeve rests, the contacting faces of the collar and sleeve being provided with posts and notches which interlock to prevent rotation of the unit.

3. A movable support comprising side frames, each frame including front and back legs, a unit connecting such frames, said unit including at each end a sleeve which is mounted upon one leg of the side frame, and means for locking said unit in position upon the side frame, said locking means at each side frame including a collar on the leg on which the sleeve rests, the contacting faces of collar and sleeve being provided with posts and notches which interlock to prevent rotation of the sleeve, and means for holding said sleeve in interlocking contact with said collar.

4. A movable support comprising side frames, each frame including front and back legs, a unit connecting such frames, said unit including at each end a sleeve which is mounted upon one leg of the side frame, and means for locking said unit in position upon the side frame, said locking means at each side frame including a collar on the leg on which the sleeve rests, the contacting faces of collar and sleeve being provided with posts and notches which interlock to prevent rotation of the sleeve, and a nut in mesh with a nipple carried by the leg

on which the sleeve is mounted for holding the sleeve in interlocking contact with said collar.

5. A movable support comprising side frames, each frame including a front leg, a back leg and a bar connecting the tops of said legs, said back leg being at an obtuse angle to said bar, and a unit connecting said frames, said unit including a sleeve at each end thereof and a crossbar joining said sleeves, each sleeve surrounding and being carried by a back leg of a frame and resting upon a collar fixed to said leg, said collar including a pair of diametrically arranged posts and the lower face of the sleeve having two pairs of diametrically opposed notches in which the posts rest when the support is in the set-up or collapsed positions.

6. A movable support comprising side frames, each frame including a front leg, a back leg and a bar connecting the tops of said legs, said back leg being at an obtuse angle to said bar, and a unit connecting said frames, said unit including a sleeve at each end thereof and a crossbar joining said sleeves, each sleeve surrounding and being carried by a back leg of a frame and resting upon a collar fixed to said leg, said collar including a pair of diametrically arranged posts and the lower face of the sleeve having two pairs of diametrically opposed notches in which the posts rest when the support is in the set-up or collapsed positions, the pair of notches which receive the posts when the support is set up being equal in length to the posts and the other pair of notches which receive the posts when the support is collapsed being longer than the posts.

7. A movable support comprising side frames, each frame including a front leg, a back leg and a bar connecting the tops of said legs, said back leg being at an obtuse angle to said bar, and a unit connecting said frames, said unit including a sleeve at each end thereof and a crossbar joining said sleeves, each sleeve surrounding and being carried by a back leg of a frame and resting upon a collar fixed to said leg, said collar including a pair of diametrically arranged posts and the lower face of the sleeve having two pairs of diametrically opposed notches in which the posts rest when the support is in the set-up or collapsed positions, the pair of notches which receive the posts when the support is set up being equal in length to the posts and the other pair of notches which receive the posts when the support is collapsed being longer than the posts so that one end of each post engages one end of such notch and the other ends of the post and notch are spaced apart.

8. A movable support comprising side frames, each frame including a front leg, back leg, an upper bar connecting the tops of said legs and a brace bar connecting the legs below and parallel to the upper bar, and a unit connecting said frames, said unit including a sleeve at each end thereof which sleeves surround the back legs of the frames and rotate thereon to permit the rotation of the frames relative to the unit to collapse the support with the unit between the side frames, and a crossbar joining said sleeves, said back legs being rearwardly inclined, said crossbar being at an angle to each sleeve approximately equal to the angle between the brace bar and back leg of each frame, so that when the support is so collapsed it rests solely upon the front legs of the frames.
